(57) **CLAIM**

The ornamental design for the shoe cover, as shown and described.

DESCRIPTION

FIG. 1 is a front perspective view of a shoe cover of the present invention;

FIG. 2 is a first side view of the shoe cover of the present invention;

FIG. 3 is a second side view of the shoe cover of the present invention;

FIG. 4 is a third side view of the shoe cover of the present invention;

FIG. 5 is a fourth side view of the shoe cover of the present invention;

FIG. 6 is a top plan view of the shoe cover of the present invention;

FIG. 7 is a bottom plan view of the shoe cover of the present invention; and,

FIG. 8 is a front perspective view of the shoe cover of the present invention stretched over, and conforming to, a shoe. The broken lines of FIGS. 7 and 8 are for illustrative purposes only and form no part of the claimed design.

1 Claim, 4 Drawing Sheets
